UNITED STATES PATENT OFFICE.

CHARLES OWENS, OF CHATTANOOGA, TENNESSEE, ASSIGNOR TO MONTAGUE MAILING MACHINERY COMPANY, A CORPORATION OF TENNESSEE.

INKING-RIBBON MECHANISM.

1,162,643.

Specification of Letters Patent. Patented Nov. 30, 1915.

Application filed January 9, 1915. Serial No. 1,396.

To all whom it may concern:

Be it known that I, CHARLES OWENS, citizen of the United States, residing at Chattanooga, Tennessee, have invented certain new and useful Improvements in Inking-Ribbon Mechanism, of which the following is a specification.

My invention relates to ribbon mechanism, and is designed more especially for use in connection with printing or addressing machines in which the impressions are made from individual printing or record plates through an inking ribbon.

The invention consists in the features of construction and arrangement and combination of parts hereinafter described and particularly defined by the appended claims.

In the accompanying drawings Figure 1 is a plan view of the inking ribbon mechanism with a part of the supporting frame; Fig. 2 is a rear view of Fig. 1 with parts in section; Fig. 3 is an end elevation of Fig. 1.

In these drawings, 1 and 2 indicate the inking ribbon spools which are loosely mounted upon the ends of a tubular shaft 3. Each spool has a spring wire 4 attached thereto at its ends, Fig. 3, the middle portion of this spring wire being seated in a groove at the end of the tubular shaft so that the spool, while free to turn on the shaft, is under frictional restraint due to the wire spring bearing on the shaft. The shaft 3 is turned step by step in accordance with the demands of the impressions being made, and this may be accomplished in various ways. In the particular construction shown, a ratchet wheel 5 is fixed on the shaft, and this is engaged by a pawl 6 reciprocated in any suitable way through connections with the impression head. The shaft is mounted in bearings 7 which are attached to the frame of the machine, and it is held against longitudinal movement by collars 8 fixed thereon and bearing on the inner sides of the brackets. The tubular shaft has a clutch member at each end fixed thereto, as at 9, 10, said clutch members having teeth around their outer edges to be engaged by pawls or driver members 11, 12, carried by the ribbon spools and movable in a direction parallel with axis thereof. Each of these detents or drivers is in the form of a wire bent into loop or the general form of a staple, with its parallel arms guided in openings in the spool, and its crosspiece 13 extending substantially

diametrically of the spool and shaft. The pawls are adapted to engage the teeth of their respective clutches, and thus impart the movement of the tubular shaft to the ribbon spools. The engagement of the pawls with their respective clutch members 9 and 10 is controlled by a weighted member one for each spool, as shown at 14, 15, these weighted members being pivotally mounted at 16 to ears on the outer faces of the spools. Each weighted member has an arm 17 adapted to bear on the crosspiece 13 of the corresponding pawl or driver to move the same into engagement with its clutch member 9 or 10, and this action takes place when the inking ribbon is unwound and the weighted inner end of the controller lever is allowed to drop. When the spool has the ribbon wound thereon, the weighted lever will be held in substantially horizontal position by the ribbon bearing on the inner weighted end, and while so held the end 17 of said weighted lever is held removed from engagement with the pawl or driver 11 or 12, as the case may be, and this ribbon spool is free to turn on the tubular shaft for the unwinding of its ribbon. As soon, however, as the ribbon is unwound, the weighted lever will fall into the position shown at the right of Fig. 2, and the pawl or driver will be moved by the weighted lever to engage the clutch member, for instance, the member 10, and therefore this ribbon spool will be connected up to the tubular shaft and will be moved step by step through said shaft and the pawl and ratchet mechanism 5 and 6.

Extending through the hollow shaft 3 is a rod 18 engaging at its ends the pawls or drivers 11 and 12 by bearing on the cross bars 13 thereof, from which it will be noticed that when one driver is thrown into engagement with its clutch member to impart positive motion to its ribbon spool for winding the ribbon thereon, the same action will move the rod 18 through the hollow shaft and the pawl or driver at the other spool will be released from its clutch member so that this spool may turn on and in respect to the hollow shaft in order that its ribbon may unwind and be wound upon the other spool. This rod, therefore, controls the engagement of each pawl or driver with its respective clutch member.

I claim as my invention:—

1. In combination ribbon spools coaxially

- arranged, a clutch and pawl for each ribbon spool for driving the same, said pawl extending through the ribbon spool and movable parallel with the axis thereof, a member restrained by the ribbon and serving to throw the pawl into engagement with the clutch when the ribbon is unwound from either spool, and a connection extending from one spool to the other for throwing the pawl of one spool out of connection with its clutch when the pawl of the other spool is thrown into connection with its clutch, substantially as described.
2. In combination inking ribbon spools coaxially arranged, a driving mechanism for each spool, including a clutch, and a pawl movable parallel with the axis of the spool, means at each spool controlled by the ribbon for throwing the pawl at the corresponding spool into operation when the ribbon at said spool becomes unwound, and a connection extending from one spool to the other for throwing the pawl of said other spool out of operation when the driving mechanism of the first spool is thrown into operation, said connection consisting of a straight rod movable in the direction of its axis, substantially as described.
3. In combination a pair of ribbon spools holding the ends of the inking ribbon, a tubular shaft on which the said spools are mounted to have movement relative to said shaft, a driving connection at each spool between the same and the said shaft, a controller at each spool for throwing the driving connection into operation when the ribbon at said spool becomes unwound, and a rod extending through the tubular shaft and operating upon the driving mechanism of the other spool to release the same when the first spool becomes connected with the tubular shaft, and means for operating the tubular shaft step by step, substantially as described.
4. In combination a pair of ribbon spools holding the ends of the inking ribbon, a hollow shaft upon which said spools are mounted to have movement relative thereto, a clutch member on the hollow shaft at each end thereof adjacent the spool, a pawl or driver for each spool having a portion extending parallel with the axis of the spool, and adapted to engage the clutch member, and having a portion extending across the axis of the hollow shaft, a weighted member for each spool which, when released by the unwinding of the ribbon, will operate

the pawl or driver into engagement with the clutch member, and a rod extending through the hollow shaft from one pawl or driver to the other for releasing one pawl from engagement with its clutch member when the other pawl is thrown into connection with its clutch member, substantially as described.

5. In combination ribbon spools coaxially arranged, a clutch and pawl for each ribbon spool for driving the same, said pawl extending through the ribbon spool and movable parallel with the axis thereof, a member restrained by the ribbon and serving to throw the pawl into engagement with the clutch when the ribbon is unwound from either spool, and a connection extending from one spool to the other, and through said spools for throwing the pawl of one spool out of connection with its clutch when the pawl of the other spool is thrown into connection with its clutch, substantially as described.

6. In combination a pair of ribbon spools arranged coaxially, a shaft coaxial with the axis of the ribbon spools, clutches fixed to said shaft between the spools, pawls, one for each spool supported and carried thereby and movable parallel with the axis of the spools to engage with and disengage from the clutches, means controlled by the unwinding of the ribbon from the spools for operating the pawls, and a rod extending from one pawl to the other for releasing one of said pawls when the other is set into engagement with its clutch.

7. In combination a pair of ribbon spools coaxially arranged, a shaft, clutches on said shaft one for each spool, a pawl for each spool, said pawls extending through the spools to engage the clutches, means controlled by the ribbon and engaging the pawls at the outer sides of the spools for moving said pawls inwardly through the spools to engage the clutches when the ribbon becomes exhausted, and a connection extending from one spool to the other for releasing the clutch at one spool when the pawl at the other spool is set, substantially as described.

In testimony whereof, I affix my signature in presence of two witnesses.

CHARLES OWENS.
